UNITED STATES PATENT OFFICE.

SPIROS C. MARKATOS, OF NEW YORK, N. Y.

HAT-STEAMING DEVICE.

Application filed June 12, 1923. Serial No. 644,980.

To all whom it may concern:

Be it known that I, SPIROS C. MARKATOS, a citizen of the United States, residing at New York city, in the county of New York and 5 State of New York, have invented certain new and useful Improvements in Hat-Steaming Devices, of which the following is a specification.

This invention relates to hat steaming devices and more particularly to a novel and improved attachment for hot water and steam boilers wherein the generated steam may be introduced in a hood or steam chest as when blocking or pressing a hat form.

15 The primary object of my invention is to provide an attachment for steam boilers and the like including a foot operated control for the introduction of steam to the hood or steam chest whereby the operator may have 20 the free use of the hands during the steaming operation.

Another object of my invention is to provide a hood or steam chest in connection with a steam boiler including provision for 25 a foot operated control for the passage of the steam and embodying further provision whereby condensation is effected within the steam chest and dry steam is permitted to 30 pass entirely about the hat or form and escape upwardly through the top of the chest.

To enable others skilled in the art to fully comprehend the underlying features of my invention that they may embody the same in the various modifications in structure and 35 relation contemplated, drawings depicting a preferred form have been annexed as a part of this disclosure and in such drawings, similar reference characters denote corresponding parts throughout all the views, of 40 which,

Figure 1 is a perspective view showing the attachment in connection with a steam boiler.

Figure 2 is an enlarged sectional view 45 showing the hood or steam chest in its relation with the steam control.

Figure 3 is a plan of the cover or closure for said steam chest.

Figure 4 is a bottom plan of the steam 50 vessel.

Figure 5 is a sectional view of the locking means for said closure.

Figure 6 is a sectional view through the steam inlet pipe.

55 Referring now to the drawings wherein like

reference characters designate corresponding parts throughout the several views, 5 designates in its entirety a steam boiler which may be heated by gas or any other means, 60 which boiler is provided with a gage 6 of any conventional type. Reference being had to Figures 1 and 2 I have shown a hollow support or standard 7, having an enlarged base 8 which may be secured on the floor adjacent to the boiler, the upper end of said support being threaded for connection to the extension 9 of a casting 10. A short pipe 11 is threaded to one side of the casting and extends into the 70 boiler 5 so that the generated steam may pass into the hood or steam chest, subsequently to be referred to. The casting 10 is provided with a passage 13 which is in communication with a vertical passage extending upwardly through the casting. A steam chest 15 having a frusto-conical bottom 16 is adapted to be positioned on the top face of the casting 10 and is secured thereto by a lock nut 17 threaded internally for engagement with the threaded head 18 of the casting. Extending upwardly through the vertical passage in the casting, I have provided an inlet pipe 20, the upper end of which is threaded to receive the internally threaded 80 extension 21 of a substantially cone-shaped steam vessel or baffle 22. This baffle constitutes a support for a hat block or form commonly used in steaming hats, the bottom 23 of said baffle having a plurality of apertures 90 24 whereby the condensed steam and water vapor may fall to the bottom of the steam chest. The frusto-conical bottom 16 is provided with an aperture which is in communication with an angularly disposed passage 95 25 in the casting whereby the water may flow downwardly and outwardly through the flexible connection 26 to the waste.

It will be observed that the lock nut 17 is provided with a coiled spring 27 100 inferiorly thereof which engages the lower end of the extension 21. The inlet pipe 20 is somewhat enlarged at the lower end 28 thereof and extends through a bushing 29. A seat 30 within the casting constitutes a 105 stop for the inlet pipe and closes the passage 13 to the steam. A plurality of radially disposed apertures 31 in the inlet pipe permits the steam to pass upwardly into the steam vessel or baffle when the said inlet pipe and steam vessel are depressed by the link connection 32 connected as at

33 to the lower end of the said inlet which operation is affected by the foot lever 34 pivotally connected at 35 to the support or standard 7.

5 In this manner it will be readily seen that the operator may depress the foot lever 34 so that the apertures 31 are in communication with the passage 13 whereupon the steam may enter the vessel. This operation 10 is thus effected and pressure is released from the foot lever, the inlet pipe will move upwardly and thus close the openings. When the steam enters the steam vessel, the moisture or water or condensation flow 15 downwardly through the aperture 23 and out through the flexible pipe 26 and the dry steam passes and circulates throughout the hood and steam chest as clearly shown.

The closure or cover 36 is hingedly connected as at 37 to a bracket 38, preferably formed integral with the cover as suggested by Figure 2 of the drawings. The cover, however, is provided with an elliptical flanged opening 39, whereby the steam may 25 pass directly upward and out of the hood or steam chest so that the operator may steam the brim of a hat only, if desired. In addition, the front wall of the opening is curved as indicated at 40, whereby the operator may grip and seize the same to raise 30 the cover. The said cover is also provided with an interior bead 41, which engaged the rolled or curved edge 42 of the hood or steam chest forming a tight fit. A locking lever 43 having a clamping head 44 is piv-

otally connected to the top of the cover so that when the said cover is in engagement with the top of the hood or steam chest, it may be tightly clamped thereto by depressing the handle 43 in the manner suggested 40 by Figure 5 of the drawings.

While I have illustrated and described my invention with some degree of particularity, I realize that in practice various alterations therein may be made. I therefore 45 reserve the right and privilege of changing the form of the details of construction or otherwise altering the arrangement of the correlated parts without departing from the spirit of the invention or the scope of the 50 appended claims.

Having thus described my invention, what I claim as new and desire to secure by United States Letters Patent is:—

In a hat renovating apparatus, the combination of a boiler, a casting and an offset support connecting the casting to said boiler, a steam chamber mounted on the casting, a combined inlet pipe and valve extending through the casting and into the 60 chamber, a combined steam separating baffle and hat support attached to the upper end of the inlet pipe, said inlet pipe having apertures communicating with the interior of the casting when the valve is in 65 open position and foot operated mechanism attached to the lower end of the inlet pipe.

In testimony whereof I affix my signature

SPIROS C. MARKATOS. [L.S.]
